Patented Apr. 23, 1912.

UNITED STATES PATENT OFFICE.

HUGH L. WILLOUGHBY, OF PHILADELPHIA, PENNSYLVANIA.

AEROPLANE-ENGINE-CONTROLLING MECHANISM.

1,024,303.

Specification of Letters Patent.

Patented Apr. 23, 1912.

Application filed August 28, 1911. Serial No. 646,300.

To all whom it may concern:

Be it known that I, HUGH L. WILLOUGHBY, a citizen of the United States, residing at Philadelphia, in the county of Philadelphia and State of Pennsylvania, have invented new and useful Improvements in Aeroplane-Engine-Controlling Mechanism, of which the following is a specification.

10 This invention relates to controlling mechanism for the engines of aeroplanes and particularly to a pedal controlled arrangement disposed for operation by the right foot of the aviator and whereby the throttle valve may be fully closed and the sparking circuit positively broken without requiring the aviator to pursue a complex manipulation of levers or other devices or to assume any unusual positions in attaining the 20 result sought.

It is well understood that the most important point in running an aeroplane is to have the engine operate at full speed in the air and never vary from a given number of 25 revolutions except during descent, when a slowing of the speed of the engine is required in order to finish with a full stop at the landing. Heretofore numerous accidents both to the aeroplanes and aviators 30 have occurred owing to the failure of the engine controlled mechanism to operate to positively shut off the throttle valve and to break the sparking circuit.

The purpose of this invention is to avoid 35 accidents by providing a foot-controlled mechanism for shutting off the throttle valve and breaking the sparking circuit with certainty by little or no effort on the part of the aviator and through the medium of simple mechanism that may be quickly operated.

In the drawing: Figure 1 is a sectional elevation of a portion of an aeroplane of that type in which the propeller is in advance of the engine and showing the features of the invention applied thereto. Fig. 2 is a top plan view of the engine cylinders and throttle valve showing the controlling bar or slide and a portion of the operating means for the latter.

The numeral 5 designates a frame having a lower base support or platform 6, and in suitable position thereon the aviator's seat 7 is secured in rear of the engine or motor 8 of any approved type, having a shaft 9 projecting therefrom to drive the propeller 10.

The features of the invention are shown applied to an aeroplane in which the aviator sits in rear of the engine and the latter drives a forward propeller. It will be understood that the improved pedal control for the engine embodying the features of the invention may be applied to any form of aeroplane or engine, and instead of working wholly in advance of the aviator a simple 65 and obvious reversal of parts of the mechanism may be adopted to permit a similar operation in rear of the position of the aviator. Furthermore, a particular form of throttle slide or control and sparking plug 70 and circuit completing means is shown, but it is proposed to apply the features of the invention to any throttle valve operating means and sparking plug circuit to which they may be applicable, and the invention is 75 not limited to use with any precise form of engine, throttle valve operating means and sparking plug circuit, and those shown in the drawing have been adopted simply to illustrate one practical form of application 80 of the invention.

Mounted on the base support 6 at a suitable distance in advance of the seat 7 for the aviator is a bracket 11 embodying an upwardly projecting and forwardly inclined 85 arm 12 having a spring contact 13 secured to the base portion thereof and in advance of the same. Slidingly mounted in the arm 12 above the contact spring 13 and also movably extending through the base support 6 in advance of the bracket 11 is a pedal rod or bar 14 having a head 15 at its upper rear end for engagement by the foot of the aviator and connected at its lower end to one arm of a bell-crank lever 16 movably 95 depending from a bracket 17 attached to the under side of the support 6. The remaining arm of the bell-crank lever 16 is connected by a link rod 18 movably extending upwardly through the support 6 10 to one arm of a second bell-crank lever 19 fulcrumed on a bracket 20 projecting rearwardly from a forward portion 21 of the frame, the other arm of the bell-crank lever 19 having a spring 22 attached thereto and to the said bracket 20 and also connected by a link rod 23 to a third bell-crank lever 24 fulcrumed on a bracket 25 projecting rearwardly from the upper portion of the frame and having a slotted arm 26 to receive a pin 27 of the throttle controlling slide or bar 28. The contact spring 13

is included in the sparking circuit of the engine, and fixed on the pedal rod 14 to move therewith is a contact projection or ball 29 which is shiftable over the spring 13 and while in engagement with the latter the sparking circuit is maintained in closed condition, but as soon as the ball 29 is moved off the contact spring 13, the sparking circuit is instantly broken.

10 The throttle controlling slide 28 is slideable at its forward extremity in a suitable guide 30 and at its rear extremity moves through an upright 31, the said rear extremity of the slide being formed with a shoul-
15 dered enlargement 32 to drop over the lower portion of the rear edge of the wall of a slot 33 formed in the upper extremity of the upright 31. The rear locking extremity 32 of the slide 28 is forced down-
20 wardly when the shoulder thereof coincides with the inner edge of the lower wall of the slot 33 by a pressure spring 34 secured to the upright 31 above the slide. The rear end of the slide within easy reach-
25 ing distance of the aviator has an operating head 35 by means of which the slide may be released from locking position and permitted to be moved to open the throttle and start the engine. The lock
30 of the slide 28 operates only when the latter is moved a maximum distance to fully close the throttle valve. The slide 28, as shown, is provided with yielding bridging contacts 35^a on its under side to engage the
35 conductors 36 of the cylinders, said conductors extending in adjacent to the sparking plugs 37, as well understood in the art, and as heretofore indicated the sparking plugs 37 are in electrical circuit with the
40 contact spring 13. The slide 28 also has a transverse slot 38 formed therein to receive a projection or pin 39 of a lever 40 connected to the stem of a throttle valve 41, the latter being of any approved type. When
45 the slide 28 is operated, the lever 40 will be shifted in opposite directions in accordance with the direction of movement of the slide to partially open or close or fully open or close the throttle valve in accordance with
50 the control of the engine desired during certain operations of the aeroplane.

The spring 22 operates to hold the pedal rod 14 and ball 29 fully up in the position shown by Fig. 1, and when the latter parts
55 are in such position the throttle valve 41 is wide open, and the distance of "up-play" can be set to give full speed or number of revolutions that may be desired. During the flight of the aeroplane the operator may
60 slow down the engine by pressing downwardly on the pedal rod 14 with the right foot to control the aeroplane in volplaning or for other purposes as may be found necessary, and a downward pressure on the
65 rod 14 operates through the bell-cranks 16,

19 and 24 and the connecting link rods 18 and 23 to correspondingly shift the slide 28 and proportionately shut off the throttle valve 41. When the pedal rod 14 is relieved of foot pressure of the aviator the spring 22 immediately comes into play and restores the parts to normal position and the throttle valve 41 is fully opened. This partial depression of the pedal rod does not break contact or engagement of the ball 29 with the spring 13, but when it is desired to fully shut off the engine in making a landing, a stronger downward pressure is exerted on the pedal rod 14 and just prior to the disengagement of the ball or contact projection 29 with the spring 13 the slide 28 will have been shifted rearwardly a sufficient distance to lock the same by means hereinbefore explained and fully shut off the throttle valve, and immediately subsequent, in view of the continued downward pressure exerted on the pedal rod, contact of the projection 29 with the spring 13 will be broken or the said projection will move off the spring, as shown by dotted lines in Fig. 1, and immediately the sparking circuit is broken and all liability of the engine starting until the slide 28 is manually released from its locked position will be prevented. When the slide 28 is locked the retractile effort of the spring 22 will be overcome and the pedal lever 14 will remain in depressed position, but as soon as the aviator releases the rear locked extremity of the slide 28 the spring 22 again acts and restores the pedal lever 14 and the ball or contact 29 to normal position, as shown by full lines in Fig. 1. On making a landing the thrust of the whole body of the aviator in a forward direction without any mental action whatever and while the foot is in engagement with the upper end of the pedal rod 14 will shut off the gas, break the sparking circuit and stop the engine and thereby hold the propeller in fixed position until it is desired to again start the engine, and this same operation may be pursued either in the air or on the ground. The improved controlling mechanism hereinbefore explained will be found exceptionally advantageous for the purpose for which it has been devised, and its use will avert accidents now frequently experienced, and furthermore, it will be observed that the pedal mechanism works exactly opposite to the accelerator of an automobile to meet radically different conditions.

What is claimed is:

1. In controlling mechanism for aeroplane engines, the combination with the engine throttle valve and the spark plug circuit, of a slide connected to the throttle valve, a pedal device connected to the slide and having means for restoring the same to normal position when released, and a

- contact included in the sparking plug circuit and slidably engaged directly by a portion of the pedal device to control the sparking circuit, the pedal device being operable 5 to completely shut off the throttle valve prior to the breaking of the spark plug circuit and the portion of the pedal device engaging the contact being wholly shiftable off the latter.
- 10 2. In controlling mechanism for aero- plane engines, the combination with the engine throttle valve and the spark plug circuit, of a slide connected to the throttle valve, a pedal device connected with the 15 slide of the throttle valve to operate the throttle valve to partially or wholly close and open the latter and provided with means for maintaining and breaking the sparking circuit and also operable to wholly 20 shut off the throttle valve prior to breaking the sparking circuit.
3. In controlling mechanism for aero- plane engines, the combination with the engine throttle valve and the spark plug circuit, of a slide connected to the throttle valve, the slide being provided at one extremity with automatically operating lock- 25
- ing means to hold the same against movement when the throttle valve is completely closed, and foot operated mechanism connected to the slide to partially or wholly close or partially or wholly open the throttle valve and operable to fully close the throttle valve prior to breaking the sparking circuit. 30
4. In controlling mechanism for aero- plane engines, the combination with the engine throttle valve and the sparking circuit, of a slide connected to the throttle valve and having an automatically locking extremity, the slide being locked against movement 35 when the throttle valve is fully closed independent of manual retention, and foot operated mechanism connected to the slide and adapted to be actuated to partially or wholly close or open the throttle valve and subsequent to the closing of the latter to break the sparking circuit. 40
- 45

In testimony whereof I have hereunto set my hand in presence of two subscribing witnesses.

HUGH L. WILLOUGHBY.
